US00D833090S

(12) **United States Design Patent** (10) Patent No.: **US D833,090 S**
Leick et al. (45) Date of Patent: ** Nov. 6, 2018

(54) **LITTER SCOOP**

- (71) Applicant: **Doskocil Manufacturing Company, Inc.**, Arlington, TX (US)
- (72) Inventors: **Sarah Leick**, Farmers Branch, TX (US); **David Veness**, Fort Worth, TX (US); **Sunil Pinto**, Arlington, TX (US)
- (73) Assignee: **DOSKOCIL MANUFACTURING COMPANY, INC.**, Arlington, TX (US)
- (**) Term: **15 Years**
- (21) Appl. No.: **29/629,489**
- (22) Filed: **Dec. 13, 2017**

Related U.S. Application Data

- (62) Division of application No. 29/557,482, filed on Mar. 9, 2016, now Pat. No. Des. 815,782.
